John Eeward,
ATTORNEY.

UNITED STATES PATENT OFFICE.

CLIFFORD H. RAMSEY, OF PATERSON, NEW JERSEY, ASSIGNOR TO JAMES L. MORRISON
MACHINE CO., OF PATERSON, NEW JERSEY, A CORPORATION OF NEW JERSEY.

HYDRO-EXTRACTOR.

1,210,836.

Specification of Letters Patent. Patented Jan. 2, 1917.

Application filed May 27, 1916. Serial No. 100,415.

To all whom it may concern:

Be it known that I, CLIFFORD H. RAMSEY, a citizen of the United States, residing at Paterson, in the county of Passaic and State 5 of New Jersey, have invented certain new and useful Improvements in Hydro-Extractors, of which the following is a specification.

This invention relates to means for lubricating bearings of the class wherein the 10 rotating element rotates at high speed on an upright axis, as in the case of so-called hydro-extractors or centrifugal machines, and it consists in certain improvements, 15 hereinafter pointed out, whereby lubrication of such bearings is effected in a way calculated to keep exposed surfaces of the machine free of lubricant and to confine the lubricant against being thrown off by the 20 rotating element onto the contents of the basket or receiver part of the latter.

In the accompanying drawings, in which the invention is fully illustrated, Figure 1 is a vertical sectional view of a hydro-extractor 25 containing my improvements; Fig. 2 is a vertical sectional view, on a larger scale, of parts including immediately the upper bearing; Figs. 3 and 4 are horizontal sectional views on the lines $x-x$ and $y-y$ of Fig. 2; and, Fig. 5 is a side elevation of the 30 rotating bearing part or bushing.

a is a liquid receptacle having a drain outlet b and its bottom elevated centrally, as at c ; and d is a frame arranged upon 35 the receptacle a .

e is a vertical shaft which carries the basket or other reticulated receiver f for the fabrics or the like from which the liquid is to be extracted centrifugally. A step 40 bearing is afforded for this shaft by a socket g suitably secured in a hole h formed centrally in the bottom of the receptacle a and by the sleeve i secured in and concentrically of the socket g and in spaced relation thereto and containing a bushing j , 45 said sleeve and bushing being radially perforated, as at k .

The upper bearing for shaft e , vertically above the step bearing, is arranged in the 50 arch d' of frame d , and is constructed as follows: A sleeve l having a reduced lower end m is secured by screws n penetrating a flange o at its upper end in a vertical hole p formed in the arch d' of the frame. Into this 55 sleeve, which has threading on the inside at

its upper end, is screwed a bushing or bearing part q , which on the inside is conical, the taper being in the upward direction; at its upper end it has a flange provided with spanner holes r . When the bushing q has 60 been adjusted up or down, it may be held against turning by a lock nut s having spanner holes t .

Screwed into the lower reduced end of the sleeve l and standing upright therein is a 65 thimble u , which forms with the sleeve an annular lubricant well, the top of the thimble being appreciably below that of the sleeve.

The shaft e has secured thereon, as by 70 the key v , an exteriorly conical bushing or bearing part w , the taper of which is upward. As shown, said bushing is secured at its upper portion to the shaft, and its lower portion depends into the well formed by 75 sleeve l and thimble u . One or other of the conical surfaces of the bushings q and w , as shown in the drawings the bushing w , has formed in its conical surface reverse spiral 80 grooves x . Once the shaft has been stepped in the step bearing with its bushing w contained in sleeve l so that its lower portion depends into the well formed by said sleeve and thimble, bushing q is introduced and 85 screwed down until it is in coöperating relation, to form a journal, with bushing w , whereupon the lock nut s is set.

The shaft has an axial lubricant passage y extending therethrough from end to end. In this passage is a constant level lubricant 90 retarder consisting in the present case of a plug z fixed in the passage and having its upper end reduced and a vertical bore 2 extending upwardly from its lower end into its upper reduced end and further having lateral openings 3 leading from said bore to the exterior of its reduced end. From a point below the level of the openings 3 but opposite the reduced portion of the plug z an inclined port 4 extends from passage y 100 through the shaft and bushing w to the exterior of the latter, the outer end of said port being slightly above the lubricant level of the retarder indicated in Fig. 2 at 5.

Keyed to the shaft e below the sleeve l is 105 a catch-well 6 into which the reduced portion m of said sleeve depends, the catch-well preferably having an inwardly projecting lip or flange 7 surrounding said reduced portion m . Leading from the well 6 inwardly 110

at an incline a hole 8 is formed in the shaft *e*, and in this hole is fitted a tubular spout or nozzle 9 whose inner end is substantially exactly in the axial line of the shaft. The 5 lubricant, as oil, is fed to the upper end of the passage *y* from a cup 10 having a delivery tube 11.

The rotary member including the shaft *e* and basket *f* may be rotated by any suitable 10 means. In the present instance the power is derived from a motor 12 and transmitted through a sprocket and chain connection 13 to a horizontal shaft 14 journaled in frame *d* and carrying a conical face plate 15 bearing 15 against a cone 16 fitted on shaft *e*.

The lubricant being allowed to drip from the cup 10 and pipe 11 into the shaft it first fills up to the level 5 at the retarder *z* and then overflows and falls into the step bearing, which in time becomes filled with oil, 20 the overflow from the step bearing passing out at the drain outlet with the liquid thrown off from the basket. So long as the rotary structure *e*—*f* is not rotating no oil 25 is delivered to the upper bearing. But during rotation, centrifugal force impels oil checked by the retarder *z* to flow up the inclined port 4, so that it comes between the contiguous faces of the bushings *q* and *w*, 30 to be then spread over said faces by the spiral grooves *x*. In time, oil may accumulate in the well *l*—*u*, eventually overflowing its inner wall (thimble *w*). The overflow will fall into the catch-well 6, from whence 35 it falls through the spout 9 into the step bearing.

An important feature of the invention is the constant level retarder *z* which keeps a certain quantity of oil in reserve ready to 40 be delivered to the upper bearing upon the machine being started and at the same time allows any surplus due to the oil being left to drip from the oil cup while the machine is stopped for short period to overflow and 45 escape to the lower bearing; flooding of the upper bearing with oil is a serious objection in machines of this character, because when there is a superfluity of oil it is likely to work out of any means for confining it onto 50 other parts of the machine to ultimately fall on the contents of the basket or be thrown by centrifugal action directly upon them. In the present construction the oil, as will be obvious, is delivered to the upper bearing 55 only when it is required.

Oil admitted to the lower bearing enters at the bottom and is discharged at the top, above the level of the water draining off through the outlet *b*, whereby the water is 60 not only kept from the rotating shaft but from the lower bearing, and said bearing always has the benefit of only oil circulating through it.

The overflow from well *l*—*u* falling into 65 catch-well 6 is drained from the latter by

spout 9 when the machine is stopped, the oil in the catch-well never accumulating to such an extent during a running period as to be thrown out past flange 7 by centrifugal force. To prevent the more or less copious 70 flow of oil down passage *y* from being driven by centrifugal force up the drain outlet from the catch well into the latter I have provided the spout 9; so long as this spout projects beyond the surface of the passage 75 into the same it accomplishes the purpose, but it is best to have it project so far that its end will be at the point where the centrifugal force is *nil*—to the axis of the passage.

Having thus fully described my invention, what I claim as new and desire to secure by Letters Patent is:—

1. In combination, a support and an upright rotary member having a bearing in 85 the support and a lubricant passage extending through the bearing portion of said member, said member having a constant-level lubricant retarder in the passage and a lubricant port leading laterally from the 90 retarder to the bearing and delivering to the latter at a point above the constant level of the retarder.

2. In combination, a support and an upright rotary member having a bearing in 95 the support and a lubricant passage extending through the bearing portion of said member, said member having a constant-level lubricant retarder in the passage and an inclined lubricant port leading laterally 100 from the retarder to the bearing and delivering to the latter at a point above the constant level of the retarder.

3. In combination, a support having an annular lubricant well including interiorly 105 thereof a bearing part, and an upright rotary member penetrating said well and having a bearing part depending into the well and operatively engaging the bearing part thereof, said member having means to feed 110 a lubricant substantially axially through the same and then into the well.

4. In combination, a support having an annular lubricant well including a bearing part, and an upright rotary member penetrating said well and having a bearing part 115 depending into the well and operatively engaging the first-named bearing part, one of said bearing parts having its bearing surface tapered, and one of said bearing parts 120 being vertically adjustable relatively to the other.

5. In combination, a support having upper and lower bearings, and an upright rotary member journaled in said bearings and 125 having a lubricant passage extending therethrough, uninterrupted from above the upper bearing to and delivering into the lower bearing, said member having a constant-level lubricant retarder in said passage and 130

a lubricant port leading laterally from the retarder to the upper bearing.

6. In combination, a support having upper and lower bearings, and an upright ro-

5 tary member journaled in said bearings and having a lubricant passage extending from above the upper bearing to and delivering into the lower bearing, said member having a constant-level lubricant retarder in said 10 passage and a lubricant port leading from the retarder to the upper bearing and delivering to the latter at a point above the constant level of the retarder.

7. In combination, a support having a 15 bearing, and an upright rotary member journaled in the bearing, said support and member having means to lubricate the bearing and a lubricant catch well arranged below the bearing, said means including a lubricant passage extending axially through said 20

member from a point relatively above to a point below the catch well and said catch well having a delivery spout projecting into said passage.

8. In combination, a liquid receptacle having a drain outlet in its bottom portion and a part of its bottom elevated relatively to the drain outlet, a step-bearing in the elevated part of the bottom of said receptacle, a basket-carrying rotary shaft journaled in said 25 step-bearing and having a lubricant passage leading therethrough from above the step-bearing and delivering thereto at a low point therein, the bearing having means to deliver the used lubricant into said receptacle onto 30 the elevated part of said bottom, and means to rotate said shaft.

In testimony whereof I affix my signature.

CLIFFORD H. RAMSEY.
